SIGN FOR STREETS, ETC.

Ever A. Ferm, Chicago, Ill.

Application June 14, 1949, Serial No. 99,046

9 Claims. (Cl. 40—130)

1

This invention relates to signs which are used for indicating the names of streets, as well as for other purposes, and more particularly to signs of this type which are rendered legible by light rays emanating from another source.

It has heretofore been proposed to construct signs for streets, etc., of light-penetrable materials in order to enhance legibility by utilizing light rays at the rear of the sign which emanate from a source other than the sign itself, such as from a street lamp or natural daylight.

One of the most familiar of the prior art devices comprises four assembled and right-angularly disposed glass panels which are carried by a lamp post below the street lamp in order that either the light from the street lamp or ordinary daylight may penetrate the glass panels from the rear and thus enhance the legibility of the sign whether the field (or background) be transparent and the indicia opaque, or vice versa. Some of the prior art devices of the type referred to utilize angularly disposed mirrors for diverting the light rays from above onto and through the backs of the glass panels.

So far as I am aware, the prior art devices described hereinbefore have always been constructed of glass and for this reason were frequently broken, thus necessitating expensive and troublesome replacement.

Other prior art signs of which I am aware utilize plastic materials, and for this reason are not so easily broken, but they are somewhat more difficult to read than those which have been described hereinbefore.

It is among the objects of the present invention to provide a sign for streets, etc., which is adapted to utilize rays emanating from another source, and which is so constructed as to provide extreme legibility.

Another object is the attainment of the immediate foregoing in a device which is of enhanced durability.

Still another object is the provision of a device of the type referred to, and possessed of extreme legibility and enhanced durability, which is simple and inexpensive to manufacture and install.

A further object is to provide a pair of spaced sign-forming elements so constructed and arranged as to provide an overhung area of comparative shadow on the side from which the sign will be read by an observer, thereby substantially increasing the light contrast and readability of the designation.

A still further object is to arrange a pair of

2

sign-forming elements of the type referred to hereinbefore in such manner that light will directly penetrate either or both of the assembled elements or will be directed from one to the other by reflection to a degree which is dependent upon the angle of incidence of rays emanating from the light source.

A still further object is to provide a unit all sides of which offer smooth unobstructed surfaces to facilitate cleaning and thereby reduce maintenance costs to a minimum, at the same time avoiding cleaning contact with, and weather exposure to, the indicia element sealed in between the two laminations.

A still further object is to provide a sign of the type described which comprises a pair of elongate members assembled to form a V-shaped trough which is open at the bottom, the inner surfaces of the elongate member being composed, at least in part, of light-penetrable material, the elongate members being provided with indicia, and the inner surfaces of the indicia being light-reflective whereby the amount and/or intensity of light passing through the oppositely disposed elongate member is enhanced; the V-shaped trough which is open at the bottom preventing the accumulation of rain and snow, leaves from trees, and other debris.

A still further object is the attainment of the foregoing with a combination of elements which may be readily formed of plastic materials which are possessed of substantial durability.

This invention, then, comprises the features fully described and as particularly pointed out in the claims, the following description and annexed drawings setting forth in detail certain illustrative embodiments of the invention, these being indicative of but several of a number of ways in which the principles of the invention may be employed.

In said drawings:

Figure 1 is a side elevation of a sign embodying the teachings of the present invention, and an end view of a second and similar sign which is disposed slightly higher and at 90° with respect thereto.

Figure 2 is an enlarged sectional view taken on the line 2—2 of Figure 1 and illustrating laminae of the component elements of the sign per se.

Figure 3 is a view similar to that of Figure 2, but illustrating a modification.

Figure 4 is an enlarged sectional view taken on the line 4—4 of Figure 1.

Figure 5 is a fragmentary elevational view taken on the line 5—5 of Figure 4.

Referring more particularly to Figure 1 of the drawings, the letter A designates a lamp post of conventional design, the same being provided with a lateral extension B which carries a street lamp C on its outer end.

In accordance with the teachings of the present invention, there is provided a pair of elongate rectangularly-shaped members 2 which are assembled in spaced parallelism in such manner as to form a V-shaped trough which is open at its bottom. Each of these elongate rectangularly-shaped members 2 comprises an inner or backing sheet or portion which is formed, at least in part, of light-penetrable material, preferably of a colored translucent plastic. Disposed outwardly of but immediately adjacent the outer surface of each of the elongate rectangularly-shaped members 2 is the indicia or sign designation, as shown at 3, the latter preferably being in the form of a perforated sheet.

According to all forms of the present invention, light is to penetrate the assembled elongate rectangularly-shaped members 2; and this may be accomplished by having said members 2 formed wholly or in part of light-penetrable material and the indicia or sign designation 3 of opaque material. The members 3 may either have openings to define the sign designation, in which case the sign field or background will be opaque and dark and the designations lighted, or they may comprise opaque sign designations, in which case said field or background will be lighted and the designations opaque and dark.

In either case, the inner surfaces of the indicia, or sign designation, 3 are prepared to provide substantial reflectivity as by coating, as at 4, with a mirrored surface, white paint, etc. In this manner, light reflectivity as between the rearward surfaces of the elongate rectangularly-shaped members 2 is provided. According to a preferred embodiment, a transparent cover 5 of sheet-like material is provided for the entireties of the outer surfaces of the sign-forming elements or such portions thereof as are light penetrable. Thus, the indicia 3 is sealed between the elongate rectangularly-shaped, colored translucent member 2 and the clear or colorless transparent cover 5 which not only provides for protection against the weather, etc., but also facilitates cleaning.

The foregoing construction and arrangement is such that with a pair of panels (each comprised of the elements 2, 3, 4 and 5) assembled to form a V-shaped trough which is open at the bottom and the assembly is mounted to extend laterally from a lamp post at a position which is somewhat below the street lamp, light rays, whether from natural daylight or emanating from the street lamp, will, to a very substantial extent, penetrate the light-penetrable portions of both of the sign-forming panels. Some light rays will directly penetrate the light-penetrable portions of either or both of the pair of V-assembled sign-forming panels, while other light rays will be diverted from the reflective inner surfaces 4 of the indicia 3 onto the elongate rectangularly-shaped member 2 which forms the back of the oppositely disposed sign-forming panel. This reflective attachment will supply light to the indicia of the opposite panel to provide for a light source which is disposed off the vertical centerline of the V-shaped trough, which is often the case in the daytime when the sun moves in its orbit.

The members 2, which, as previously men-

tioned, are preferably of a colored translucent plastic, may have a relatively high coefficient of reflection so that a portion of the light entering the V-shaped trough will be reflected by these members and a portion transmitted to their respective indicia. The trough is so arranged that the light reflected from one of the members 2 will strike the other of said members to supply its indicia with light. Thus the reflecting action of the members 2 will assist that of the indicia 3 to light the opposite panel of the sign.

In Figure 2 of the drawings, it will be noted that the upper and lower edges of the elongate rectangularly-shaped backing member 2 are bent outwardly at right angles, as shown at 9, in order to protect the edges of the assembled elements; while in Figure 3, the upper and lower edges of the assembled elements are provided with protective caps 10 which may be formed of suitable plastic material.

Referring to Figures 4 and 5, I have disclosed an acceptable combination of elements for assembling the pair of elongate rectangularly-shaped members 2 and mounting them on a suitable standard, such as a conventional lamp post. More specifically, these elements for assembling and mounting the elongate rectangularly-shaped members 2 comprise a pair of end brackets 12 and 14, each of which is shaped to make suitable contact with the ends of the said elongate rectangularly-shaped members. These end brackets 12 and 14 are held in firm contact with the ends of the elongate rectangularly-shaped members 2 by rivets 16 which also serve to hold together the laminar component elements of the sign per se and form a unitary construction.

One of the end brackets (i. e., that which is indicated at 12 in Figures 1, 4 and 5) is provided with means whereby the unit may be suspended from a lamp post, or other standard. According to the construction shown most clearly in Figures 4 and 5, the end bracket 12 is provided with upper and lower pairs of outwardly extending lugs 12a, each lug being stamped from the material of the end bracket, and the lugs of each pair occupying substantially the same horizontal plane. These outwardly extending lugs, or projections, 12a which are formed by semi-perforating the bracket 12 are adapted to contact the exterior of the lamp post A, or other standard, with the slots formed by the stamping operating accommodating standard adjustable connecting straps 20 which encircle the lamp post at appropriate horizontal levels, as shown most clearly in Figure 5.

It is contemplated that the material of the end bracket 12, and accordingly of the outwardly extending lugs 12a, be such as will enable the lugs to provide spring tension on the adjustable straps 20 to maintain permanent tightness of the same.

As stated previously, the embodiment shown in Figure 2 (as well as in Figures 1 and 5) utilizes an elongate rectangularly-shaped member 2 (forming the inner, or backing, portion of the sign) having longitudinal edge portions which are right-angularly bent, as shown at 9, thereby forming a channel section. Such an element will be extruded from suitable translucent plastic material, whether it be clear or colored.

In any case, it is contemplated that the various plastic materials be chemically fused together at their edge and end portions to form a single unit with the indicia member permanently sealed within the lamination.

According to all of the forms of the present

invention which are illustrated in the drawings and described hereinbefore, the backing member (comprising the elongate rectangularly-shaped members) are light-penetrable, while the superposed indicia or sign designations may be either transparent or opaque, as desired, provided, however, the inner faces of the indicia or sign designations are light reflective.

The sign of the present invention is rendered extremely brilliant when utilizing an inner member 2 which is of colored light-penetrable plastic material, a perforated indicia sheet 3 superposed on the outer surface of the member 2, and a clear transparent sheet or cover 5 overlying the outer surface of the perforated indicia sheet. Such an inner member 2 (being of colored light-penetrable material) appears to gather the light, diffuse and uniformly distribute, as well as concentrate its intensity at the perforations where permitted to pass through.

While I have shown and described several specific embodiments of the present invention, it will be readily understood by those skilled in the art that I do not wish to be limited exactly thereto, since various modifications may be made without departing from the scope of the invention as defined in the appended claims.

I claim:

1. A sign adapted to utilize light rays from an external source, such as the sun, comprising a pair of members assembled to form a V-shaped trough open at the top, said members having indicia defining means, each of said members being partially light reflective and partially light transmissive, the shape of said trough being such that light entering through the top of the trough and striking one of said members will be partially reflected to the other of said members and partially transmitted through said first-mentioned member, the light reflected to said other member being partially transmitted through said member, the light transmitted through both of said members cooperating with said indicia defining means to provide a lighted sign.

2. A sign adapted to utilize light rays from an external source, such as the sun, comprising a pair of members assembled to form a V-shaped trough open at the top and bottom, said members having indicia defining means, each of said members being partially light reflective and partially light transmissive, the shape of said trough being such that light entering through the top of the trough and striking one of said members will be partially reflected to the other of said members and partially transmitted through said first-mentioned member, the light reflected to said other member being partially transmitted through said member, the light transmitted through both of said members cooperating with said indicia defining means to provide a lighted sign.

3. A sign adapted to utilize light rays from an external source, such as the sun, comprising a pair of indicia defining members assembled to form a V-shaped trough open at the top and bottom, each of said members being partially light reflective and partially light transmissive, the shape of said trough being such that light entering through the top of the trough and striking one of said members will be partially reflected to the other of said members and partially transmitted through said first-mentioned member, the light reflected to said other member being partially transmitted through said member, the light transmitted through both of said indicia defining

members cooperating with these members to provide a lighted sign.

4. A sign adapted to utilize light rays from an external source, such as the sun, comprising a pair of indicia defining members assembled to form a V-shaped trough open at the top and bottom, each of said members being partially light reflective and partially light transmissive, and translucent members mounted on the inner surfaces of said indicia defining members, the shape of said trough being such that light entering through the top of the trough and passing through one of said translucent members to strike one of said indicia defining members will be partially reflected to the other of said translucent members and partially transmitted through said first-mentioned indicia defining member, the light reflected to said other translucent member being partially transmitted through said other indicia defining member, the light transmitted through both of said indicia defining members cooperating with said members and their respective translucent members to provide a lighted sign.

5. A sign adapted to utilize light rays from an external source, such as the sun, comprising a pair of indicia defining members assembled to form a V-shaped trough open at the top and bottom, each of said members being partially light reflective and partially light transmissive, and colored translucent members mounted on the inner surfaces of said indicia defining members, the shape of said trough being such that light entering through the top of the trough and passing through one of said translucent members to strike one of said indicia defining members will be partially reflected to the other of said translucent members and partially transmitted through said first-mentioned indicia defining member, the light reflected to said other translucent member being partially transmitted through said other indicia defining member, the light transmitted through both of said indicia defining members cooperating with said members and their respective translucent members to provide a colored lighted sign.

6. A sign adapted to utilize light rays from an external source, such as the sun, comprising a pair of indicia defining members assembled to form a V-shaped trough open at the top and bottom, each of said members being partially light reflective and partially light transmissive, translucent plastic members mounted on the inner surfaces of said indicia defining members, and light transmissive plastic members on the outer sides of said indicia defining members covering both said indicia defining members and said translucent members, the shape of said trough being such that light entering through the top of the trough and passing through one of said translucent members to strike one of said indicia defining members will be partially reflected to the other of said translucent members and partially transmitted through said first-mentioned indicia defining member, the light reflected to said other translucent member being partially transmitted through said other indicia defining member, the light transmitted through both of said indicia defining members cooperating with said members and their respective translucent members to provide a colored lighted sign.

7. A sign adapted to utilize light rays from an external source, such as the sun, comprising a pair of indicia defining members assembled to form a V-shaped trough open at the top and bottom, each of said members being partially light

reflective and partially light transmissive, translucent plastic members mounted on the inner surfaces of said indicia defining members, light transmissive plastic members on the outer sides of said indicia defining members covering both said indicia defining members and said translucent members, and means adjacent the edges of said inner and outer plastic members to provide weatherproof joints between them and seal off said indicia defining members, the shape of said trough being such that light entering through the top of the trough and passing through one of said translucent members to strike one of said indicia defining members will be partially reflected to the other of said translucent members and partially transmitted through said first-mentioned indicia defining member, the light reflected to said other translucent member being partially transmitted through said other indicia defining member, the light transmitted through both of said indicia defining members cooperating with said members and their respective translucent members to provide a colored lighted sign.

8. A sign adapted to utilize light rays from an external source, such as the sun, comprising a pair of translucent members assembled to form a V-shaped trough open at the top and bottom, each of said translucent members being partially light reflective and partially light transmissive, and members having openings to define indicia mounted on the outside of each of said translucent members, the shape of said trough being such that light entering through the top of the trough and striking one of said translucent members will be partially reflected to the other of said translucent members and partially transmitted through said first-mentioned translucent member, the light reflected to the other of said

translucent members being partially transmitted through said member, the light transmitted through both of said translucent members passing through the openings in said indicia defining members to provide a lighted sign.

9. A sign adapted to utilize light rays from an external source, such as the sun, comprising a pair of translucent members assembled to form a V-shaped trough open at the top and bottom, each of said translucent members being partially light reflective and partially light transmissive, and indicia mounted on the outside of each of said translucent members, the shape of said trough being such that light entering through the top of the trough and striking one of said translucent members will be partially reflected to the other of said translucent members and partially transmitted through said first-mentioned translucent member, the light reflected to the other of said translucent members being partially transmitted through said member, the light transmitted through each of said translucent members outlining said indicia to provide a lighted sign.
